UNITED STATES PATENT OFFICE.

EDWIN T. BASKIN, OF INDEPENDENCE, MISSOURI.

GLOVE.

1,105,239.

Specification of Letters Patent. Patented July 28, 1914.

Application filed June 21, 1911. Serial No. 634,539.

To all whom it may concern:

Be it known that I, EDWIN T. BASKIN, a citizen of the United States, residing at Independence, in the county of Jackson and 5 State of Missouri, have invented certain new and useful Improvements in Gloves; and I do declare the following to be a full, clear, and exact description of the invention, such as will enable others skilled in the art to 10 which it appertains to make and use the same. reference being had to the accompanying drawings, and to the letters and figures of reference marked thereon, which form a part of this specification.

15 My invention relates to gloves or mittens and more particularly to working men's gloves; the object of the invention being to provide a glove wherein the thumb is so constructed and arranged, relative to the 20 other parts, that the glove may be worn on either hand.

In accomplishing this object, I have provided the improved details of structure hereinafter described and illustrated in the accompanying drawings, wherein:—

Figure I illustrates a glove, constructed according to my invention. Fig. II is a detail view of the body portion of the glove. Fig. III is a detail view of the thumb member.

Referring more in detail to the parts:— 1 designates the body of the glove, which is preferably formed from a single piece of material, such as cotton fabric, and has the 5 fingers 2; the seam 3 preferably following one of the finger seams, so that the stitching of said seam and the finger seam may be continuous. At one edge of the body portion, the material is cut away, and the loose 10 edges of the thumb portion 4 are lapped thereover and stitched from near the base of the thumb to a point adjacent to the wrist position, in order to provide loose flaps 5 on the thumb portion and the wrist portions 6 on the body 1, so that the thumb part will fit close at the base of the hand, but is free from there to the wrist in order that the glove may comfortably fit either hand. The 15 ends of the glove members are preferably 20 provided with extended wrist pieces 5' and

6', in order to better protect the wearer's wrist.

As a fastener for the glove, I provide a strap extension 7 on one of the wrist flaps 5, and a strap extension 8 of greater length on 55 the other flap, and provide the extension 7 with button-holes 7' and the extension 8 with a button 8', so that the glove may be fastened to the wrist when in use.

In using the glove, it is pulled over the 60 hand in the usual manner and the loose wrist strap extensions fastened. With the thumb piece stitched to the edge of the body, as shown, it is immaterial upon which hand the glove is worn, as it will fit over 65 the right or left hand. When using a working man's glove, the palm of either the right or left hand becomes worn before a like part of the other glove, so that it is ordinarily necessary to discard the pair when one glove 70 is worn out.

With a glove of the present construction, should the palm of one glove become worn before that of the other, the gloves may be 75 changed about so that they may be used until both are worn out.

Having thus described my invention, what I claim as new therein and desire to secure by Letters-Patent is:—

1. A glove comprising a body member and 80 a thumb member, the body member having finger portions, a palm portion and a wrist portion; said palm and wrist portions having a deep incut in one side, the thumb member having a thumb portion, a ball portion 85 and wrist flaps; said ball portion being open at one side and secured to the palm portion of the body member, strap extensions of unequal length on the wrist flaps, adapted to lie on each side of the wrist portion of the body member, and fastening devices on said strap extensions for securing the glove to the wrist.

2. A glove comprising a body member 95 consisting of a single piece of material cut to form wrist, palm and finger portions, with the stock for the first and fourth fingers left uncut and folded at the center thereof, and with portions of the second and third fingers lying adjacent the free 100

ends of said member; the free ends of said member and the free edges of the finger portions being stitched, and a thumb member consisting of a single piece of material cut to form thumb, ball and wrist portions, folded at the center thereof and stitched along the free edges of the thumb portion; the free edges of the ball portion

being stitched to the free edges of the palm portion, for the purpose set forth. 10

In testimony whereof I affix my signature in presence of two witnesses.

EDWIN T. BASKIN.

Witnesses:

MYRTLE M. JACKSON,
ARTHUR W. CAPS.
